UNITED STATES PATENT OFFICE.

WILLIAM C. EVANTS, OF MYRTLE CREEK, OREGON.

FRUIT-DRIER.

SPECIFICATION forming part of Letters Patent No. 240,111, dated April 12, 1881.

Application filed July 20, 1880. (No model.)

To all whom it may concern:

Be it known that I, WILLIAM C. EVANTS, of Myrtle Creek, Douglas county, Oregon, have invented an Improvement in Fruit-Driers, of which the following is the specification.

This invention relates to apparatus for drying fruit, vegetables, fish, meat, &c., in which the article to be dried is exposed on horizontal trays to the action of artificial heat within a drying-chamber.

The invention consists, first, in a novel combination of fire-boxes and flue-tubes, whereby a large and efficient radiating-surface is formed and heated; secondly, in provision for readily cleaning said flue-tubes, so as to preserve their efficiency; thirdly, in a novel combination of parts, constituting a superior tray-elevator for use when a continuous operation is an object.

Figure 1 of the accompanying drawings is a perspective view of a fruit-drier, illustrating my invention. Fig. 2 is a plan or horizontal section of the same on the line 1 2, Fig. 3. Fig. 3 is a vertical longitudinal section. Figs. 3^a and 3^b are face views of one pair of the tray-elevator rods, illustrating their operation. Fig. 4 is a perspective view, and Fig. 5 a longitudinal section, showing one of the gravitating pawls of the tray-elevator. Figs. 6 and 7 are perspective views, illustrating other details.

Like letters of reference indicate corresponding parts in the several figures.

In carrying out this invention I form a long rectangular hot-air chamber, C, having vertical walls and an open top, and at the ends of this chamber I form externally a pair of fire-boxes, B B². The walls z z', to a sufficient height for safety, including those of the fire-boxes, have been built of brick, and the brick walls at the ends of the chamber C have vertical escape-flues f f² and smoke-chambers s s² formed within them, the latter collecting the discharge from the several flues into metallic chimneys or escape-pipes P P², one at each end of the apparatus.

From the fire-box B a horizontal series of flue-tubes, r, extends to the opposite end of the chamber C and discharges into the flues f, and from the fire-box B² a like series of flue-tubes, r², extends to the flues f² in the wall adjoining the fire-box B, the respective series of flue-tubes alternating with each other, as

illustrated in Fig. 2, with the sides of adjoining tubes parallel and close to each other, forming contracted air-passages. The effect of this arrangement is to utilize the heat of the products of combustion to the utmost degree, and at the same time to equalize the distribution of heat throughout the drying-chamber without complication of parts.

Opposite the open ends of the flue-tubes r r², I form holes c c², for the insertion and removal of flue-cleaners, and I provide these holes with plugs p, one of which is shown in perspective in Fig. 6, each consisting of a cast-iron shell filled with clay or cement. My arrangement of parts facilitates making and using this provision, as the flue-tubes are all at one convenient height.

Each fire-box has a horizontal grate and ash-pit extending from front to rear, and each ash-pit is provided with an air-inlet, a', which may extend from end to end thereof, having a suitable damper, d', to regulate the supply of oxygen to the fire. Each ash-pit is also provided with a pair of ash-drawers, d, removable from its respective ends, and each fire-chamber has at front and rear a water-door, D, cast with an opening, x, at top, to provide for readily filling the same. Provision is thus made for maintaining fires of any required intensity without danger to the apparatus, and the use of cord-wood and like fuel is facilitated.

Beneath the flue-tubes r r² small air-inlets a are formed in the walls of the chamber C, and above the tubes transverse water-pipes w are arranged, to supply sufficient humidity to the hot air to prevent scorching, and also to prevent forming dry crusts on the pieces of fruit, which, without this provision, are liable to have the escape of internal moisture prevented by premature surface-drying. I form said water-pipes of L shape, as shown in Fig. 7, with the longer leg of each horizontal, and with this horizontal leg plugged or otherwise closed at its outer end, and provided at its top with small holes for the escape of vapor from the water, the short leg being vertical and open, to provide for filling the pipe.

Above the fire-proof walls above described I extend the chamber C by means of wooden walls to form the drying-chamber, which, in the illustration, consists of two sections, C' C²,

illustrating two modes of supporting and handling the fruit-trays $t t^2$. Section C' is provided with four pairs of vertical slide-rods, R R', having gravitating pawls y, Figs. 4 and 5, and connected at their upper ends by ropes or chains v v', passing over loose pulleys q q' to a reversible windlass, W, to which the respective ropes or chains are attached, so as to lower one rod of each pair and lift the other a given distance simultaneously. The several pairs of slide-rods are located at the respective corners of the tray-space within the section, and at the bottom and top of this space feed and discharge openings o n are formed in the front and rear walls, or either of them, as shown. The trays bearing the fruit are introduced through the opening o, and, by turning the windlass W first in one direction and then in the other, are raised, step by step, to the opening n. When a tray is removed through n, another is elevated to its place, and a fresh tray is introduced through o, and thus the operation proceeds. A tray just introduced through the opening o is indicated at t' in Fig. 3^a by dotted lines, and preceding trays are indicated at t t, the rod R of a pair of rods being shown in its lowest position. During the upstroke of this rod (indicated by the arrow thereon) its pawls y carry the series of trays upward half a space, lifting the tray t', for example, from the position indicated in Fig. 3^a to the position indicated in Fig. 3^b, the line o' in the latter figure indicating the level of the feed-opening. During the succeeding upstroke of the rod R' the pawls of this rod lift the lower trays to the positions indicated in full lines in Fig. 3^a, making room for another tray below. While one rod of each pair is ascending the other is descending, the pawls y of the descending rods being forced back into the recesses of the rods in passing the trays t, as illustrated by dotted lines in Fig. 5. As soon as the pawls pass below the trays they drop into effective position. By employing a pair of slide-rods at each corner a relatively short stroke is rendered sufficient.

Section C² of the drying-chamber is simply provided with cleats and bridge-bars b beneath openings m, to provide for introducing and supporting its complement of trays t, which may be as many as ten or more without locat-

ing the upper tray too far from the radiator-tubes. The openings m are provided with tightly-fitting doors to confine the heat.

In connection with my arrangement of heat-generating devices, any preferred method of supporting and handling the trays may be adopted. The apparatus may also be modified as to materials and details of construction, the number of tubes and water-pipes, and the like, and the apparatus may be used for drying vegetables, fish, meat, &c., without departing from my invention.

I have found that the tubes w may be made effective means of introducing the vapor of acidulated or preservative liquids, as sulphurous acid, into intimate contact with the fruit, with great advantage to the latter.

I do not claim herein this method of treating fruit, nor my said L-shaped water-tubes w, but may claim the same in another application for patent to be filed hereafter.

I claim—

1. In a drying apparatus, the combination, substantially as herein described, of a pair of fire-boxes at the respective ends of the hot-air chamber, a pair of flue-walls at opposite ends of said chamber, and two series of flue-tubes extending in opposite directions from end to end of said chamber, and connecting the respective fire-boxes with the flues in said flue-walls, for the purposes set forth.

2. The fire-boxes B B², provided with the cleaner-holes c c², and plugs p, in combination with the horizontal series of flue-tubes r r² in line with said cleaner-holes, for the purpose set forth.

3. The combination of the windlass W, ropes or chains v v', and pulleys q q', and the slide-rods R R', having gravitating pawls y, said slide-rods R R' being arranged in pairs at the respective corners of the tray-space, and one of each pair raised while the other is lowered, as herein described, for the purpose set forth.

In testimony whereof I have signed my name to this specification in the presence of two subscribing witnesses.

WILLIAM C. EVANTS.
